UNITED STATES PATENT OFFICE.

ARTHUR T. DUNCAN, OF CLINTON, MISSOURI.

CRANKING DEVICE FOR EXPLOSIVE-ENGINES.

1,292,274.

Specification of Letters Patent.

Patented Jan. 21, 1919.

Application filed February 27, 1918. Serial No. 219,497.

To all whom it may concern:

Be it known that I, ARTHUR T. DUNCAN, a citizen of the United States, residing at Clinton, in the county of Henry and State 5 of Missouri, have invented a new and useful Cranking Device for Explosive-Engines, of which the following is a specification.

This invention relates to cranking devices for explosive engines, one of its objects being to provide a device of this character 10 which can be applied readily to an automobile or other structure on which the engine is mounted and which will act positively to prevent injury to the user should the engine 15 back fire during the starting operation.

A further object is to provide a simple and compact structure which will not readily get out of order and which will automatically lock the parts when they are shifted 20 out of their normal relative positions as the result of back firing.

Another object is to provide means for automatically coupling together the parts when unlocked thus to reset the device.

With the foregoing and other objects in view which will appear as the description proceeds, the invention consists of certain novel details of construction and combinations of parts which will be hereinafter 25 more fully described and pointed out in the claims, it being understood that various changes within the scope of the appended claims without departing from the spirit of the invention.

In the accompanying drawings the preferred form of the invention has been shown.

In said drawings

Figure 1 is a side elevation of the device constituting the present invention.

Fig. 2 is an enlarged section therethrough on line 2—2, Fig. 1.

Fig. 3 is a section on line 3—3, Fig. 2.

Fig. 4 is a plan view of a portion of the casing of the device and showing the latch 45 used in connection therewith.

Fig. 5 is a section on line 5—5, Fig. 4.

Fig. 6 is a view partly in section and partly in elevation of a slightly modified form of device.

Fig. 7 is a section on line 7—7, Fig. 6.

Referring to the figures by characters of reference, A designates a clutch such as ordinarily used on the shaft of an engine

for starting purposes and B designates a portion of the engine supporting structure 55 which, in the present instance, can be the front end of the chassis of an automobile. The present invention includes a clutch shaft 1 mounted to slide and rotate within an opening C in the structure B and this 60 shaft has a pin 2 adapted, when the shaft is shifted longitudinally, to engage the clutch A. A collar 3 is secured to the shaft 1 in any manner desired, as by means of a pin 4, and formed in the periphery of the 65 collar at intervals are notches 5.

A cylindrical housing 6 is mounted on the shaft 1 and mounted for rotation on the shaft and within the housing is a disk 7 which is interposed between the collar 3 and 70 the back end of the housing which, as shown, is closed. A ring 8 is secured to the shaft 1 by means of a pin 9 or the like and serves to hold the closed end of the housing snugly 75 against the disk 7.

A finger 10 extends from the closed end of the housing and is adapted, when the shaft 1 is moved longitudinally in one direction, to enter an opening formed within the structure B, as shown at 11. Thus the 80 housing is held against rotation. Formed upon the inner surface of the wall of the housing 6 is an annular series of ratchet teeth 12 and fitted within the open end of the housing is a disk 13 from the center of 85 which extends a sleeve 14 housing the end portion of the shaft 1. Another shaft 15 extends into and is secured within the sleeve, this shaft 15 having a crank 16 secured thereto, as shown in Fig. 1. 90

Annular shoulders 17 and 18 are formed on the inner faces of the disks 7 and 13 and lugs 19 are formed on the disk 13 at desired intervals with their outer faces flush with the shoulder 18 and with their ends 95 in contact with the disk 7. Screws 20, or other fastening means, are extended through the disk 7 and into the lugs 19 and thus securely connect the two disks 7 and 13.

Arranged between the disks 7 and 13 and bearing on the shoulders 17 and 18 is a ring 21 having openings 22 in its periphery preferably arranged in pairs. Pawls 23 and 24 are arranged in pairs in the ring and journaled in said ring so as to move therewith. 100 These pawls extend through the respective 105

openings 22, one pawl of each pair being provided with a finger 25. A spring 26 is interposed between the finger of each pawl 24 and the adjoining pawl 23 and thus serves to hold both pawls normally projected through the openings 22 and into engagement with the ratchet teeth on the housing 6.

A dog 27 is arranged between the ring 21 and the collar 3, this dog having trunnions 28 which bear within the disks 7 and 13. A lug 29 extends from one end of the dog 27 and is normally seated in one of the notches 5, and a finger 30 extends from the other or pivot end of the dog and projects loosely into an opening 31 formed within the ring 21.

An ear 32 is extended inwardly from the ring 21 and a spring 33 is interposed between this ear and one of the lugs 19, thus normally to press the ring 21 against the finger 30 on the dog 27 and project the lug 29 into one of the notches 5.

A slot 34 is formed in the disk 13 near its periphery and slidably mounted therein is a spring controlled latch 35, as shown in Figs. 4 and 5. A notch 36 is formed in the edge of ring 21 and is so located that when the disks are rotated a short distance in a counter-clockwise direction within the housing 6 and relative to the ring 21, the latch will spring into the notch and lock the disks against return movement, thus holding the spring 33 under compression.

Assuming that the latch 35 is disengaged and that all of the other parts are in their normal positions, the device is used as follows: The shaft 1 is pushed longitudinally to couple with the clutch A and to bring the finger 10 into the opening 11. The crank 16 is then given a rotation in a clockwise direction and, as the housing 6 is held fixed, the pawls 23 and 24 will slip over the teeth 12 and the dog 27 will pull, through the lug 29, upon the collar 3 and shaft 1, thus to rotate the clutch A. However, should the engine kick or back fire, the ring 21 would be held against counter-clockwise movement by the pawls 23 and 24 engaging the ratchet teeth 12 and the collar 3, which rotates with the shaft 1 will pull through the dog 27 upon the disks 7 and 13, moving them against the action of the spring 33 a short distance. This will cause the finger 30 to swing within the opening 31 and lift the dog lug 29 out of engagement with the collar 3. Simultaneously with this action the latch 35 springs into the notch 36. Thus the ring 21 and crank 16 are locked against counter-clockwise movement, the spring 33 being held under compression and the dog 27 secured in lifted position. Consequently the shaft 1 can rotate backwardly with no danger of injury to the user of the crank. By pulling the latch 35 out of the notch 36 the spring 33 will be released and the disks

and ring will readjust themselves automatically so that the dog 27 will reengage the collar 3.

If preferred, and as shown in Figs. 6 and 7, the crank arm 37 may be attached directly to the sleeve 38 on the front disk 39 and the shaft 40, corresponding with the shaft 1, can be extended entirely through the sleeve 38 and provided with a knob 41. The shaft is angular in cross section and by pushing inwardly on the knob 41 the shaft can be caused to couple to the clutch A shown in Fig. 1. The front disk 39 can be assembled with the housing 42 by a ring 43 screwed into the housing and said housing can be held fixed by ears 44 extending therefrom and fastened to the supporting structure by bolts or the like. In all other respects this modified form of the device is the same as that shown in Figs. 1 to 5.

What is claimed is:

1. A device of the character described including a non-rotatable housing having an annular series of ratchet teeth therein; a ring mounted for rotation in the housing; pawls carried by the ring and normally engaging the teeth; a shaft having a notched portion revoluble therewith and surrounded by the ring; a disk; a crank for rotating the disk; a dog revoluble with the disk and normally engaging the notched portion of the shaft; a projection upon the dog and engaging the ring; a spring bearing against the ring and disk to hold the disk and dog in their normal positions, and means for automatically locking the dog and disk out of their normal positions when shifted in one direction.

2. A device of the character described including a non-rotatable housing having a ratchet; a ring mounted for rotation in one direction in the housing; pawls carried by the ring and engaging the ratchet to hold the ring against counterclockwise movement; a shaft having a notched portion; a disk, means for rotating the disk; a dog movable with the disk and normally engaging the ring and notched portion; a spring thrusting against the disk and ring for holding the dog in its normal position, said disk being shiftable by the dog during the counterclockwise movement of the shaft and relative to the ring to disengage the dog from the shaft and place the spring under compression; and means for automatically locking the dog in said shifted position.

3. The combination with a housing held against rotation, a disk, means for rotating the disk, and a shaft having a notched portion, of a ring, co-operating means upon the ring and housing for holding the ring against counterclockwise movement; a dog carried by the disk and engaging the notched portion, a lifting finger upon the dog and engaging the ring, yielding means adapted

to be placed under compression during the
counterclockwise movement of the disk and
dog relative to the ring, and a latch carried
by the disk for engaging the ring to lock the
5 yielding means under compression with the
dog disengaged from the notched portion.

In testimony that I claim the foregoing

as my own, I have hereto affixed my signature
in the presence of two witnesses.

ARTHUR T. DUNCAN.
